UNITED STATES PATENT OFFICE

ADOLPHE ANTOINE FRANÇOIS MARIUS SEIGLE, OF PARIS, FRANCE

METHOD FOR TREATING HEAVY HYDROCARBON OILS

Original application filed December 12, 1923, Serial No. 680,059, and in France May 19, 1923. Divided and this application filed August 9, 1927. Serial No. 211,798.

The present invention relates to improvements in the methods and installations described in my prior U. S. Patent 1,702,275 and in my copending patent application No. 81,144 of January 14, 1926, for treating liquid or liquefiable hydrocarbons such as crude oils of petroleum or shale, fuel oils, gas oils and the like. According to these prior methods the hydrocarbons to be treated are vaporized and the vapors thus produced are led at a pressure slightly above or substantially equal to atmospheric pressure, to one or more retorts containing metallic chips or turnings acting to depolymerize the hydrocarbons and in which they are circulated according to a tortuous path, and the superheated gases and vapors discharged by said retorts are then subjected, in groups of cooler expanders, to successive periods of intensive and concomitant expansion and cooling, the cooling fluid used in these apparatus being boiling water.

One characteristic feature of the present invention resides in that the hydrocarbons condensed during each stage of intensive and concomitant cooling and expansion are returned to the previous cooling stage.

One very material advantage resulting therefrom resides in that the liquid fuel thereby obtained possesses the characteristic features which are described in my copending application 680,059 of December 12, 1923, of which this application is a division, and which will be hereinafter set forth.

Having thus pointed out the main feature of the method according to the invention and the advantages offered thereby I will now describe the same in detail with reference to the appended drawing which shows diagrammatically an installation for carrying out the said method, and in which:

Fig. 1 is a general view and

Figs. 2 and 3 are detail views on a larger scale.

According to the herein described process any one of the raw materials above specified, crude petroleum or shale oils, fuel oils, gas oils, etc., may be used, but in order to facilitate the comprehension of the following process, the latter will be applied to the treat-

ment of crude petroleum, wherefrom the water and the usual gasoline have been preliminarily extracted, and whose density at 15° C. is 0.897, its ignition point (in an open vessel) being 80° C. If such crude petroleum is treated by fractional distillation, no vapour is given off up to 140° C.; up to 200° C., 5 per cent is vaporized; up to 300° C., 33 per cent is vaporized; up to 350° C., 85 per cent is vaporized and the residue consists of 15 per cent of dry tar.

In a vaporization apparatus or boiler *v* suitably heated by a combustible of any kind, the oil is introduced in a continuous manner after having been preliminarily heated to 200° C. in the heater *v* (Fig. 1); this petroleum is raised in the boiler to its temperature of maximum vaporization i. e. 350° C., and the hydrocarbon vapours thus generated are then brought to the bottom of a heating 70 retort *A* of the type described in my prior Patent No. 1,702,275.

These vapours enter through the pipe *a*, according to the arrow 1, and at a pressure substantially equal to the atmosphere pressure, into the bottom of the worm retort *A* (Fig. 1), circulate upwardly by their natural ascension in the annular part *b* divided by the discs *c* (Figs. 1 and 2), and during this upward circulation they are caused to flow through metallic chips or turnings *p* laid upon said discs.

This method of circulation affords a gradual and systematic superheating of the vapours of oil or heavy hydrocarbons to a determined and easily adjustable temperature, without risk of an abrupt decomposition, such as takes place in cracking apparatus; the metallic chips which these vapours are caused to meet with upon the whole of their path will on the one hand regulate the temperature and on the other hand will exercise a catalytic action upon these hydrocarbons.

The metallic fragments used are the waste from machine work upon pieces of iron, nickel, copper and other usual metals, and they are laid upon the annular discs *c* so that the temperatures assumed by these fragments when in contact with the central heat-

ing tube *t* shall correspond to the temperatures necessary for a suitable catalytic action.

In order to increase the combined effects of heat and catalysis and to ensure an effective stirring of the hydrocarbon molecules, the circulation of the latter is alternately reversed according to the arrows 2, as shown in Fig. 2.

The hydrocarbon vapours are thus raised 10 in the retort to a temperature between 520° and 530° C., after having been subjected to a molecular transformation due to the action of the catalysts which, as is well known have more or less marked affinities for carbon and 15 hydrogen, and effect at one or another favourable temperature, a displacement of the atoms of one or the other of these two substances, which results in a mixture of compounds having physical properties (viscosity, ignition point, density, etc.) which are quite different from those of the original hydrocarbons. In short, hydrocarbons are produced in which the atomic groups are less and less condensed.

25 The vapours leaving the retort as shown by the arrow 3 are brought through pipe *k* into an expansion and cooling apparatus B consisting of two truncated cone shaped sheet metal pieces constituting a double casing, and 30 of an inner cylindrical body *e* connected by tubes *f* and *f'* with the annular chamber formed by the double casing.

The hydrocarbon vapours circulate through the annular part of the truncated cone *d* according to the arrows 4. Water is thus maintained in ebullition and at a pressure of 10 to 12 kilogrammes in the annular space between *d* and *d'* and in the cylindrical body *e*, so that a constant temperature between 200 and 220° C. will prevail in the 40 part wherein the hydrocarbon vapours circulate.

In this expansion and cooling apparatus, hydrocarbon vapours are subjected to two 45 contrary actions; on the one hand the molecular expansion produced by the change in the volume occupied by the vapours, and on the other hand the contraction due to the abrupt cooling.

50 The hydrocarbon vapours are discharged, at the lower part of the expansion and cooling apparatus B, into a space whose diameter is 10 or 15 times that of the orifice leading thereto, and hence the molecules composing 55 these vapours will "widen out," so to speak, and will hence become more voluminous; so that a molecular expansion is in fact produced.

Moreover these discharged vapours are at 60 a temperature of 530° C. and since the water boiling under pressure is maintained in the apparatus between 210° C. and 220° C., these same hydrocarbon vapours will undergo a very abrupt cooling, and their temperature 65 falls at once from 530° to 250° C., and a

molecular contraction necessarily takes place.

These simultaneous and contrary actions result in a great disturbance in the molecules, and the metallic fragments *q* disposed on the discs *g* will facilitate certain molecular rearrangements between the unduly heavy hydrocarbon vapours and the very light vapours, or even gases, and which, when properly associated together, will produce a light fuel analogous to gasoline, thus completing the physico-chemical reactions which commenced in the retort.

70 Furthermore, certain light hydrocarbons of an unstable nature, formed in the retort, are definitely fixed in the state of stable combinations by the expansion and contraction to which they are subjected.

75 But the oil has not been entirely decomposed into lighter hydrocarbons and a part of the same remains in its original state of more or less heavy hydrocarbons; the fraction distilling above 240°-250° C. is condensed and falls to the bottom of the expansion apparatus B whence it is evacuated through a pipe *h* and returns into the boiler 80 *v* after being mixed, if necessary, with a portion of petroleum not yet treated supplied by a pipe *i*, and which it will thus heat to a temperature of about 200° C. in order to prevent sudden vaporization of said fresh petroleum in the boiler.

85 The hydrocarbons remaining in the state of vapour below 250° C. and composed for the major part, of the above said light products which have just been manufactured, are 90 led (arrows 5) into a second expansion and cooling apparatus C of a like construction, but wherein the pressure of the boiling water is maintained at only 3 kilogrammes, i. e. at a temperature of about 135° C.

95 The same physical and catalytic actions are repeated in said second apparatus C, but now only upon hydrocarbons distilling below 250° C. and whereof the major part has already undergone a total transformation or a 100 partial doubling; so that the catalytic work in this second expansion and cooling apparatus is simplified, and a definite stability takes place within the mass of the hydrocarbons wherein the atoms of carbon and hydrogen, or their groups of hydrocarbon molecules, were not yet in a perfectly fixed state.

110 Those of said hydrocarbons which distil above 180° C. will condense and fall to the bottom of the second expansion apparatus C, whence they are evacuated through a pipe *m* 115 and are led to the bottom of the first expansion and cooling apparatus B.

120 The pipe *m*, as shown in the drawing (Fig. 3) opens into the above mentioned pipe *h* through which the hydrocarbons condensed in the apparatus B are returned to the boiler 125 *v*. But the hydrocarbons discharged from the apparatus B are at a temperature of 250° C., as above said, while the hydrocarbons 130

flowing down through the pipe *m* and discharged into the pipe *h* are at a temperature below 180° C. Hence, since the latter hydrocarbons are those whose boiling point is between 250° C. and 180° C., when they become mixed with those discharged from the apparatus B at a temperature of 250° C., i. e. above their boiling point, instead of flowing down through the pipe *h* together with the hydrocarbons discharged from B, they will be once more vaporized and the vapors will ascend and re-enter the lower end of the cooler-expander B. They are therein mixed with the vapours issuing from the retort A, are thus further reheated by the latter to a higher temperature and are again submitted to the intensive and concomitant cooling and expansion which takes place in B. The valves *o*¹ *o*² *o*³ are used for taking off from time to time a small amount of the various liquids for testing purposes.

The ignition point of the said product is somewhat below that of the usual gasoline extracted from petroleum, while possessing a density greater than that of the said gasoline, and a like calorific and thermodynamic efficiency.

Further characteristic features of a purely chemical nature are successively mentioned below; the new product has the same percentage composition of hydrogen and carbon as the non-inflammable and more or less heavy oils, and even viscous oils, from which it was extracted, and which, omitting their percentage of oxygen, sulphur, etc., contain as a rule from 88 to 89 parts by weight of carbon for 12 to 11 parts of hydrogen, whilst the analogous composition of the standard gasoline is from 85 to 86 parts of carbon by weight for 15 to 14 parts of hydrogen, and this whatever may be the origin and percentage composition of the crude or heavy petroleums from which the said standard gasoline has been extracted.

In short, the aggregate of light hydrocarbons composing the product according to the invention is isomeric with the aggregate of the original heavy hydrocarbons, whilst (as is known) the hydrocarbons composing the standard gasoline obtained by cracking or by a mere distillation are, on the whole, the homologues of their original hydrocarbons, due to the increase in hydrogen or the diminution in carbon of the percentage composition of the latter.

Furthermore, the hydrocarbons composing the product according to the invention are mainly unsaturated hydrocarbons, whilst most of the homologous hydrocarbons entering into the composition of the standard gasolines are saturated hydrocarbons.

A direct consequence of this latter feature is that the new product is much more sensitive to the action of certain chemical agents than the gasolines of the standard type. For

instance the sulphuric acid partially converts the new product into sulpho-conjugated derivatives or various sulphonated products whose colour varies from a bright red to a greenish brown and having strong 70 odours revealing the presence of ketone derivatives such as menthone, eucalyptol, etc.

On the contrary, chloride of calcium only forms a feeble precipitate which can be readily separated from the liquid thus purified 75 and freed from colour, and whose ether-like odour is of a very characteristic nature.

The new product can always be recognized by its odour which remains very peculiar when it is in the crude state that is to say 80 when it is discharged from the apparatus, as well as when it has been treated by one or another reagent.

This fact is all the more characteristic as it is constant, even when the origin of the 85 crude or heavy petroleum or shale oils used as raw material is changed.

A further difference between the new product and the standard gasolines extracted from petroleum resides in that these latter 90 are, as is well known, insoluble in the ethyl, methyl or amyl alcohols, unless an auxiliary or solvent suitable substance, such as ether, be used, whereas the new liquid fuel is directly very soluble in all said alcohols, and in all proportions, if the alcohols are absolute, and as far as 80 to 85 per cent of fuel in the industrial alcohols. Further, such alcoholic solutions are entirely stable, and remain liquid at a temperature of -35° C. 95

The above mentioned characteristics clearly differentiate the product according to the invention from the other light and inflammable hydrocarbons obtained from petroleum or shale, which are already known, and now will be given the principal characteristic features which differentiate the same from the equally light and inflammable hydrocarbon extracted from the coal-peat or lignite tar, and which is usually sold under the 100 denomination of "benzol".

1. When treated with nitric acid, the fractional parts of the new product which distil between 80 and 90° C., do not furnish nitrobenzene, whereas the same fractional parts 115 of benzol will furnish it in abundance.

2. The new product in the crude state has a density of 0.735 to 0.780, according to the nature of the raw material from which it has been extracted, whilst refined benzol 120 has a density of about 0.870 to 0.890.

3. A somewhat intensive cooling to -30° or -35° C. has no effect upon the new product, whereas benzol becomes frozen throughout the mass at -4° C. 125

4. Leaving out of account its small proportion of oxygen, sulphur, etc., the elementary composition of the new product is, as has been above said, from 88 to 89 parts by weight of carbon for 12-11 parts of hydro- 130

gen, whereas the average composition of benzol is 92 parts by weight of carbon for 8 parts of hydrogen.

The hydrocarbons which are not condensed in the second expansion and cooling apparatus C proceed according to the arrows 6 into an ordinary condenser γ with cold water or air circulation, in which is condensed the new liquid fuel according to the invention, and whose principal characteristic features have been above explained. Said product is then collected through the cock or valve n in one of the vessels in common use for the storage or transportation of petrols, gasoline or other volatile liquid products.

It is to be noted that the above mentioned maximum temperature of 520° - 530° C. applies to the treatment of the special oil specified, but may be widely varied according to the nature of the raw oil used, and, as a matter of fact, may be comprised between 500° and 700° C., as is well known in cracking industry.

Having now described my invention, what I claim as new and desire to secure by Letters Patent is:

1. Method for the transformation of heavy hydrocarbons comprising a preheating stage for vaporizing the raw hydrocarbon, a main heating stage which consists in heating, in a very regular and gradual manner, the vapors formed during said preheating stage, the gaseous hydrocarbons produced during said main heating stage being successively submitted to the action of catalyzers, the maximum temperature being substantially comprised between 500° C. and 700° C. and a number of successive cooling stages to which the mixture of gases and vapors issuing from said main heating stage are subjected, the cooling medium used in the first cooling stage being boiling water at a predetermined superatmospheric pressure so that the sudden drop in the temperature of said gases and vapors through said first cooling stage be at least 250° C., the condensate in each cooling stage, from the second stage on, being reheated and revaporized and then again submitted to the action of the previous cooling stage.

2. Method for the transformation of heavy hydrocarbons comprising a preheating stage for vaporizing the raw hydrocarbons, a main heating stage which consists in heating, in a very regular and gradual manner, the vapors formed during said preheating stage, the gaseous hydrocarbons produced during said main heating stage being successively submitted to the action of catalyzers, the maximum temperature being substantially comprised between 500° C. and 700° C., and a number of successive cooling stages to which the mixture of gases and vapors issuing from said main heating stage are subjected, in the presence of other catalyzers having respec-

tively their specific action at the temperatures in said cooling stages, the cooling medium in the first cooling stage being boiling water at a predetermined superatmospheric pressure so that the sudden drop in the temperature of said gases and vapors through said first cooling stage be at least 250° C., the condensate in each cooling stage, from the second stage on, being reheated and revaporized and then again submitted to the action of the previous cooling stage and of the corresponding catalyzer.

3. In the method as claimed in claim 1 the further feature residing in that the condensate in each cooling stage, from the second stage on, is reheated and revaporized by mixing the same with the hydrocarbon gases and vapors entering the previous cooling stage.

4. In the method as claimed in claim 1 the further feature residing in that the condensate in each cooling stage, from the second stage on, is reheated and revaporized by mixing the same successively with the condensate in the previous cooling stage and then with the hydrocarbon gases and vapors entering said latter stage.

In testimony whereof I have signed my name to this specification.

ADOLphe ANTOINE FRANCOIS MARIUS SEIGLE.
